UNITED STATES PATENT OFFICE.

EDWARD W. HABERMAAS, OF CINCINNATI, OHIO.

DESIGN FOR AN ORNAMENT FOR PICTURE-FRAMES.

SPECIFICATION forming part of Design No. 37,447, dated May 23, 1905.

Application filed April 20, 1903. Serial No. 153,576. Term of patent 14 years.

To all whom it may concern:

Be it known that I, EDWARD W. HABERMAAS, a citizen of the United States, and a resident of the city of Cincinnati, in the county of Hamilton and State of Ohio, have invented a new and original and ornamental Design for an Ornament for Picture-Frames, of which the following is a specification, reference being had to the accompanying drawing, forming a part hereof.

The figure is a perspective view of an ornament for a picture-frame, showing the design.

I claim—

The ornamental design for an ornament for a picture-frame, as shown.

EDWARD W. HABERMAAS.

Attest:

JOHN E. FITZPATRICK,
K. SMITH.
